(57) **CLAIM**

The ornamental design for a retention clip, as shown and described herein.

DESCRIPTION

The invention described and claimed herein may be manufactured, used, and licensed by or for the U.S. Government for U.S. Government purposes.

FIG. 1 is a perspective view of a retention clip of our new design;

FIG. 2 is a forward view thereof;

FIG. 3 is a top view thereof, the bottom view (180 degrees opposed thereto) is a mirror image thereof;

FIG. 4 is a left side view thereof;

FIG. 5 is a right side view thereof; and,

FIG. 6 is a back view thereof.
